UNITED STATES PATENT OFFICE.

JOHN P. FABER, OF DUNELLEN BOROUGH, NEW JERSEY, ASSIGNOR, BY MESNE ASSIGNMENTS, TO RANSOME CONCRETE MACHINERY COMPANY, OF PLAINFIELD, NEW JERSEY, A CORPORATION OF NEW JERSEY.

DISTRIBUTING BUCKET FOR CONCRETE-PAVING MACHINES.

Application filed June 15, 1921. Serial No. 477,681.

To all whom it may concern:

Be it known that I, JOHN P. FABER, a citizen of the United States, and a resident of the borough of Dunellen, in the county 5 of Middlesex, State of New Jersey, have invented certain new and useful Improvements in Distributing Buckets for Concrete-Paving Machines, of which the following is a specification.

10 The improvements relate to dumping buckets, and particularly to buckets of this character designed to form a part of an apparatus for mixing and distributing concrete for road paving and other work. In 15 devices of this kind it is desirable for various reasons to have the bucket provided with dumping doors at its bottom extending crosswise of the line of travel, the said doors opening outwardly and downwardly 20 when the bucket is dumped. This causes them to come in contact with the heat of materials deposited by the bucket, and sometimes with other objects when the bucket is moved and makes it desirable that 25 the said doors be arranged to swing upwardly so as to ride over such obstacles without injury thereto or to any other part. The doors should also have independent movement so that when one comes in contact 30 with an obstacle it can move to pass thereover without detrimentally affecting the other or the connection between them or the door-operating means. It is to provide for this that the present improvements are 35 primarily designed.

The improvements are illustrated in the accompanying drawings, in which Figure 1 is a side elevation of a dumping bucket, with doors at the bottom thereof embodying the improvements, and of the carriage and door-operating means; Figure 2 is a plan of the bucket of Figure 1; Figure 3 is a medial vertical section taken substantially 40 at right angles to the line of travel of the bucket showing the doors in open position, and also showing adjacent parts.

The construction illustrated in the drawings is a specimen embodiment of the improvements, and shows the best form in 45 which they have been embodied, but it is apparent that other forms may be used and that the details of construction may be varied without departing from the scope of the invention.

The bucket 1 may be of any suitable 55 shape, and is mounted on a carriage 2 traveling to and from the mixing machine on the boom 3, by means of the rollers 4. A trip and restoring mechanism for the dumping door in the bottom of the bucket is 60 provided in the links 5, 6, and 7, operated by the trip-arm 8, which is moved to close the doors when it comes in contact with the member 9 on the boom on its return to the concrete mixing machine. Its 65 bucket dumping movement may be accomplished by any suitable mechanism or by hand.

The doors 10 are hinged to the bottom of the bucket 1 at 11, and extend across the 70 bucket from side to side, at right angles to its line of travel along the boom, and are adapted to be closed by means of the link 5, operated in the manner described. This link has a sheave 12 mounted on its 75 lower end, and each door has an eye 13 secured to its inner and upper side near its outer edge. Connected at its two ends with the eyes 13 and running over the sheave 12 is a chain 14, by which the doors are 80 connected with the closing mechanism in such a manner as to permit lateral movement while they are in open position. The length of this chain is approximately equal to twice the distance from the sheave 12 85 to the connecting eye of either door when the door is closed, and as the chain travels freely over the sheave 12 the doors may swing laterally when in open position, but without changing their mean distance from 90 the operating link.

The result of this construction is that while the doors may swing freely in one direction or the other to pass over the heap of materials dumped by the bucket, or any other obstacle (see dotted lines Fig. 3), they will be tightly closed and securely held when the operating mechanism is moved to closing position. This permits the disposition of the doors crosswise of the bucket, and also enables the 95 doors to act as spreaders for the material dumped therefrom, the return movement of the bucket causing them to pass through or over the top of the material in this last operation. If the forward door strikes an 100 obstacle it will swing up thus slackening the chain 14, and if the rearward door strikes the same or another obstacle it will be per-

mitted by the slack of the chain to swing backward and upward. As the link in permitting the doors to open moves downward a sufficient distance to allow the door 5 to depend vertically from the bottom of the bucket, the length of chain is sufficient to permit both doors to assume a substantially horizontal position, if necessary, while passing over the dumped concrete or any 10 other obstacle while, at the same time, no matter what the position of the doors may be when the restoring mechanism operates they will be closed instantly, and securely held in closed position until the dumping 15 mechanism is again tripped.

What I claim is:

1. A bucket mounted to travel to and fro and to receive, convey, and dump its contents at different points, a dumping door 20 pivotally mounted on the bottom of said bucket, means for releasing said door and permitting it to open, and means for closing the said door, said means comprising a flexible connection between said door and another part of said releasing and closing means permitting movement of said door relative to the said other part and the bucket and away from its closed and normally open 25 positions and to a position in which its lower part is above its said normally open position while the door is in open position.
2. A bucket mounted to travel to and fro and to receive, convey, and dump its contents at different points, dumping doors 30 pivotally mounted on the bottom of said bucket, means for releasing said doors and permitting them to open, and means for closing the said doors, said means comprising a flexible connection between said doors and another part of said releasing and closing means permitting movement of said doors relative to the said other part and the bucket and away from their closed and normally open 35 positions and to positions in which their lower portions are above their said normally open positions while the doors are in open position.
3. A bucket mounted to travel to and fro and to receive, convey, and dump its contents at different points, dumping doors 40 pivotally mounted on the bottom of said bucket, means for releasing said doors and permitting them to open, and means for closing the said doors, said means comprising a flexible connection between said doors and another part of said releasing and closing means permitting movement of said doors relative to the said other part and the bucket and away from their closed and normally open 45 positions and to positions in which their lower portions are above their said normally open positions while the doors are in open position.
4. A bucket mounted to travel to and fro

and to receive, convey, and dump its contents at different points, a dumping door pivotally mounted on the bottom of said bucket, means for releasing said door and permitting it to open, and means for closing the said door, said means comprising a flexible connection between said door and another part of said releasing and closing means permitting movement of said door relative to the said other part and the bucket and away from its closed and normally open positions while the door is in open position, said connection comprising an attenuated flexible device secured to said door and movable lengthwise independently of said other part.

5. A bucket mounted to travel to and fro and to receive, convey, and dump its contents at different points, dumping doors pivotally mounted on the bottom of said bucket, means for releasing said doors and permitting them to open, and means for closing the said doors, said means comprising a flexible connection between said doors and another part of said releasing and closing means permitting movement of said doors relative to the said other part and the bucket and away from their closed and normally open positions while the doors are in open position, said connection comprising an attenuated flexible device fixed to the said doors and movable lengthwise independently of said other part.

6. The combination of a bucket mounted to travel to and from a mixing device and to receive, convey and dump its contents at different points, a plurality of dumping doors at the lower part of said bucket and hinged thereto to move outwardly and downwardly therefrom, vertically moving means for closing and permitting said doors to open, and a flexible member connected with said doors and with the opening and closing means, said flexible member being movable over said means to permit the said doors to swing to different positions relative to the bucket and to each other.

7. The combination of a bucket, means for mounting said bucket to travel to and from a filling device, and means for opening and closing the bottom of said bucket, comprising a movable member mounted therewith, a fixed member in the path of said movable member, doors pivotally mounted at the lower part of said bucket and arranged to open outwardly and downwardly to permit the contents of the bucket to be dumped, and a connection between said movable member and each of said doors, said connection constructed and arranged to hold both doors against movement and closed when it is in its door closing position, but permitting independent movement of the doors when the said member is in its door opening position, and said connection being positively con-

nnected with said doors and the movable member at all times.

8. In a device of the character described, the combination of a plurality of doors, a dumping bucket on which the said doors are pivotally mounted, means for closing said doors and holding them in closed position and for permitting them to open, means for moving the bucket longitudinally, and 10 a connection between said door operating means and the doors, comprising a flexible member connected with said doors and said door operating means and movable with respect thereto.

15 9. The combination of a bucket mounted to travel to and fro and to convey and deposit its contents at different points having a bottom opening, a dumping door pivotally mounted on the bottom of said bucket, means 20 for releasing said door and permitting it to open and for closing said door comprising a rigid member, said door being normally in a substantially vertical plane when open, but capable of swinging from said 25 plane in two directions, a movable part mounted on said bucket, and a flexible member connecting said door and said closing means and movable part, said connection permitting movement of the door to and 30 from said plane independent of movement of the closing means.

10. In combination with a dumping bucket mounted to travel backward and forward and to receive, convey, and deposit its 35 load at different points and return to the charging point, of a plurality of discharging doors mounted on the lower part of the bucket, means for opening and closing said doors, comprising a flexible connection between the doors movable on a part of the 40 said opening and closing means, and so constructed and arranged that the doors will move independently of the said means to and from their normal open positions in two 45 directions.

11. In combination with a dumping bucket mounted to travel backward and forward and to receive, convey, and deposit its load at different points and return to the 50 charging point, of a plurality of discharging doors mounted on the lower part of the bucket, means for opening and closing said doors, comprising a flexible connection between the doors movable on a part of the 55 said opening and closing means, and so constructed and arranged that the doors will move independently of the said means to and from their normal open positions in two directions, the said connection being such 60 that when one of the doors is moved outwardly from its normal open position the other door is moved inwardly thereby from that position.

12. The combination of a bucket mounted 65 to travel to and fro, a plurality of dumping

doors in the lower part thereof mounted to swing outwardly therefrom and disposed transversely to the line of travel of the bucket, means for opening said doors at different points along the line of travel of said bucket and for moving the bucket from its discharging position while the doors are open, and a flexible connection between said opening means and the doors movable on said opening means to cause movement of 70 one of the doors toward closed position when the other is moved from its normal open position away from its closed position.

13. The combination of a bucket mounted to travel to and fro, a plurality of dumping doors in the lower part thereof mounted to swing outwardly therefrom and disposed transversely to the line of travel of the bucket, means for opening said doors at different points along the line of travel of said bucket and for moving the bucket from its discharging position while the doors are open, and a flexible connection between said opening means and the doors movable on said opening means to cause movement of 75 one of the doors toward closed position when the other is moved from its normal open position away from its closed position.

14. The combination of a bucket mounted to travel to and fro, a plurality of dumping doors in the lower part thereof mounted to swing outwardly therefrom and disposed transversely to the line of travel of the bucket, means for opening said doors at different points along the line of travel of said bucket and for moving the bucket from 80 its discharging position while the doors are open, and a flexible connection between said opening means and the doors constructed and arranged to permit independent upward movement of the doors toward closing position, and to cause one of the doors to move inwardly and upwardly toward closing position when the other is moved outwardly and upwardly away from such position.

15. The combination of a bucket mounted to travel to and fro, a plurality of dumping doors in the lower part thereof mounted to swing outwardly therefrom and disposed transversely to the line of travel of the bucket, means for opening said doors at different points along the line of travel of said bucket and for moving the bucket from its discharging position while the doors are open, and a flexible connection between said opening means and the doors constructed 105 and arranged to permit independent upward movement of the doors toward closing position, and to cause one of the doors to move inwardly and upwardly toward closing position when the other is moved outwardly 110

115

120

130

and upwardly away from such position, said doors being free to move upwardly to pass over the load discharged from the bucket when the said load extends above their lower edges and normally projecting downwardly below the bucket in open position to have a leveling and distributing action on the said load.

16. A bucket mounted to travel to and from and to receive, convey, and dump its contents at different points, dumping doors pivotally mounted on the bottom of said bucket, means for releasing said doors and permitting them to open, and means for closing the said doors, said means comprising a flexible connection between said doors and

another part of said releasing and closing means permitting movement of said doors relative to the said other part and the bucket and away from their closed and normally open positions while the doors are in open position, said connection comprising an attenuated flexible device fixed to the said doors and movable lengthwise independently of said other part, and a rotating device on said other part over which said flexible device travels.

Witness my hand this 13th day of June, 1921, at the borough of Dunellen, in the county of Middlesex, and State of New Jersey.

JOHN P. FABER.
